DISPLAY PANEL

John M. Le Vett, Jr., and Robert R. Barnes, Lakewood,
Colo., assignors to Albar Products, Inc., Ogden, Utah

Filed Mar. 7, 1969, Ser. No. 16,107

Term of patent 14 years

Int. Cl. D6—01

U.S. Cl. D80—9

FIG. 2

FIG. 3

FIG. 4

FIG. 5

FIG. 1 is a perspective view of a display panel showing my new design;

FIG. 2 is a fragmentary top plan view thereof;

FIG. 3 is a fragmentary bottom plan view thereof;

FIG. 4 is a fragmentary front elevational view thereof, the rear being the same as the front shown; and

FIG. 5 is a fragmentary elevational view taken from one side thereof, the opposite side being the same as the side shown.

The characteristic features of my design for a display panel reside in the combination of the internal upstanding parallel spaced-apart wedge-shaped hollow divider ridges characterized in that they are formed by two curved sections anchored in spaced-apart relationship to the base and curved to meet at the top of the ridge.

We claim:

The ornamental design for a display panel, as shown and described.
